United States Patent Office

Des. 228,139
Patented Aug. 14, 1973

228,139

SPEAKER CABINET

Haruo Ishikawa, Tokyo, Japan, assignor to Kuraizura
Denki Kabushiki Kaisha, Tokyo, Japan

Filed May 23, 1972, Ser. No. 256,218

Claims priority, application Japan Nov. 30, 1971

Term of patent 14 years

Int. Cl. D14—01

U.S. Cl. D26—14 G

FIG. 1

FIG. 2

FIG. 3

FIG. 1 is a top perspective view of a speaker cabinet showing my new design.

FIG. 2 is a rear elevational view thereof.

FIG. 3 is a right side elevational view thereof.

The side not shown is plain and unornamented.

I claim:

The ornamental design of a speaker cabinet, substantially as shown and described.
